UNITED STATES PATENT OFFICE

154,333

DESIGN FOR A WRIST FLASHLIGHT OR SIMILAR ARTICLE

Sidney Schwartz, New York, N. Y., assignor to Bantam-Lite, Inc., New York, N. Y., a corporation of New York

Application February 12, 1949, Serial No. 820

Term of patent 14 years

(Cl. D48—25)

To all whom it may concern:

Be it known that Sidney Schwartz, a citizen of the United States and resident of New York city, New York, has invented a new, original, and ornamental Design for a Wrist Flashlight or Similar Article, of which the following is a specification, reference being had to the accompanying drawing, forming part thereof, in which

Fig. 1 is a perspective view of a wrist flashlight or similar article, showing my new design;

Fig. 2 is a top plan view thereof, and

Fig. 3 is a front elevational view.

I claim:

The ornamental design for a wrist flashlight or similar article, as shown.

SIDNEY SCHWARTZ.
